CHEMICAL DISCHARGE DEVICE

Albert R. Hogarth, Carrell Road, Phoenix, Md. 21131,
and James R. Dickson, 127 Hanover Road, Hanover,
Md. 21076

Filed Nov. 20, 1970, Ser. No. 26,099

Term of patent 14 years

Int. Cl. D22—99
U.S. Cl. D22—99

FIG. 1

FIG. 2

FIG. 3

FIG. 4

FIG. 1 is a perspective side and end view of our chemical discharge device.

FIG. 2 is a perspective side and end view of the opposite side thereof.

FIG. 3 is a top plan view of the device.

FIG. 4 is a bottom plan view of the device, showing our new design.

The broken line disclosure of a chemical discharge cartridge is shown for illustrative purposes only.

We claim:

The ornamental design for a chemical discharge device, as shown and described.
